UNITED STATES PATENT OFFICE.

FRANK R. MILLER, OF EVANSVILLE, INDIANA, ASSIGNOR TO GRAHAM GLASS COMPANY, OF EVANSVILLE, INDIANA, A CORPORATION OF INDIANA.

DESIGN FOR A BOTTLE.

Application filed December 19, 1923. Serial No. 8,096. Term of patent 14 years.

To all whom it may concern:

Be it known that I, FRANK R. MILLER, a citizen of the United States, residing at Evansville, in the county of Vanderburg and State of Indiana, have invented a new, original, and ornamental Design for Bottles, of which the following is a specification.

Referring to the accompanying drawings: Figure 1 is an elevation of a glass bottle showing my new design.

Figures 2 and 3 are sectional plan views, the sections being taken respectively at the planes of the lines II—II and III—III on Figure 1.

What I claim is:

The ornamental design for a bottle, substantially as shown.

Signed at Evansville, in the county of Vanderburg and State of Indiana, this 12th day of December, 1923.

FRANK R. MILLER.
